(57) **CLAIM**

We claim the ornamental design for billiard table, as shown and described.

DESCRIPTION

FIG. 1 is a perspective view showing the top, a first side, and a first end of a billiard table constructed in accordance with the present invention;

FIG. 2 is a side elevational view of the first side of the billiard table of the present invention;

FIG. 3 is a side elevational view of the first end of the billiard table of the present invention; and,

FIG. 4 is a plan view of the top of the billiard table of the present invention.

The shading on the skirt and legs of the billiard table as shown in FIGS. 1-4 is intended to designate a wood grain appearance. The second side of the billiard table of the present invention is a mirror image of the first side shown in FIG. 2. The second end of the billiard table of the present invention is a mirror image of the first end shown in FIG. 3. The bottom of the billiard table is unornamented. Lines shown in the drawings in phantom do not form a part of the claimed design, but rather define the environment with which the claimed design is utilized.
